UNITED STATES PATENT OFFICE

WILLIAM G. PURDY AND JOHN P. SPECK, OF TIFFIN, OHIO

LATTICE WORK AND MEANS FOR SUPPORTING THE SAME

Application filed March 30, 1929. Serial No. 351,321.

This invention relates to lattice work, with webs being removed. Thus a lattice is formed from a single piece of sheet metal which presents the general appearance of vertical channel bars 10 with the channel portions 12 disposed horizontally between 55 the channels 10 and in rear of the same. In mounting the lattice work, a channel bar 14 is secured within the aligned channel portions 12 near the top of the lattice and a similar channel bar 15 is secured within the 60 aligned channel portions 12 near the bottom of the lattice. These channel bars 14 and 15 extend beyond the ends of the lattice and are adapted to be secured at each end by means of suitable clamps to an upright 65

wooden post or angle bar 16 such as is commonly used to support poster and bulletin panels. These panels are preferably made of metal sections secured together in a suitable frame supported by uprights, such as 70 are shown at 16, and the lattice is mounted at the lower edge of the poster or bulletin panel.

In describing in detail the preferred form of the invention, reference will be had to the accompanying drawings, in which

25 Figure 1 is a perspective view of a lattice constructed in accordance with the invention.

Figure 2 is a horizontal section of a portion of the lattice on an enlarged scale.

Figure 3 is a vertical section thereof.

30 Figure 4 is an enlarged perspective view of one of the brackets for supporting the lattice.

Figure 5 is a similar view of another of the supporting brackets.

35 Figure 6 is a side elevation of one of the brackets secured to an upright, and with the supporting channel bar shown in section.

Figure 7 is a similar view of one of the other brackets.

40 In the form shown in the drawings, the lattice work is stamped from a single piece of sheet metal which is bent to form a series of parallel vertical channels 10 with side flanges 11, the side flange of one channel being connected to the opposed flange of the next channel by a series of webs 12. These webs are formed in the shape of horizontal channel portions running transversely to the channels 10 and having side flanges 13 bent rearwardly, the surplus metal between the

75 The upper channel bar 14 is secured at each end by a bracket 17, which is secured to the upright 16 by a bolt 18 or the like. The bracket 17 is preferably formed with an elongated slot 19 for receiving the bolt, so that the bracket may be adjusted vertically to correspond to the position of the horizontal channel portions 12 to which bar 14 is secured. The bracket 17 is formed with a horizontal seat 20 extending underneath the upper flange of the bar 14, and co-operating with this seat is a clamping member 21 which is secured to the bracket and is formed with a down turned lip 22, adapted to engage the corner edge of the bar 14.

80 Similarly the end of the lower channel bar 15 is secured to a bracket 23, which is secured to the upright 16 by means of a bolt 24 or the like. The bracket 23 is also preferably provided with an elongated slot 25 for receiving the bolt so that the bracket may be vertically adjusted to correspond to the position of the 85 lower horizontal channel portions 12. The bracket 23 is formed with a horizontally extending seat 26 on which the lower flange of the bar 15 rests and to which it is secured by a clamping member 28, the end of the seat 90

95 100

26 being turned up to form a lip 27 extending about the corner edge of the bar.

As above described, a one piece lattice construction may be manufactured very economically by stamping, and channel bars secured within certain of the horizontal channel portions of the lattice thus formed afford a certain and convenient means of supporting the same, especially when these bars are secured 10 to the uprights which support the poster panel and frame.

It is to be understood, however, that the details of construction may be considerably modified without departing materially from 15 the scope of the invention as claimed.

What we claim is:

1. A metal lattice consisting of a single piece of sheet metal formed with a series of continuous parallel channels, and webs connecting the edge of one channel to the adjacent edge of the next channel, each web portion having rearwardly turned side flanges forming channel portions extending between the continuous channels, transversely thereof 25 and in rear of the same.

2. A metal lattice consisting of a single piece of sheet metal formed with parallel channels having rearwardly turned side flanges, and connecting means between the 30 rear edge of a flange on each of said channels and a rear edge of the adjacent flange of the next channel, the connecting means between each pair of such flanges including a series of webs with openings there between, and 35 flanges turned rearwardly from the edges of the webs to form channel portions extending between the continuous channels, transversely thereof and in rear of the same.

In testimony whereof we have hereunto 40 signed our names to this specification.

WILLIAM G. PURDY.
JOHN P. SPECK.
